WAVE REPEATING SYSTEM AND APPARATUS

Philip M. Haffcke, Dobbs Ferry, N. Y., assignor to Radio Research Laboratories, Inc., New York, N. Y., a corporation of Delaware

Application April 22, 1933, Serial No. 667,358

5 Claims. (Cl. 179—171)

This invention relates to wave repeating systems, and with particularity to systems employing vapor or gas repeater devices.

An object of the invention is to provide an improved form of wave repeating system employing a repeater device having a filling of a gas or vapor in conjunction with circuit arrangements for controlling the amount of regeneration and/or sensitivity in the system.

10. The invention is in the nature of an improvement upon the type of system disclosed in co-pending application Serial No. 552,186, filed July 21, 1931.

A feature of the invention relates to a wave repeating system employing a gas or vapor filled tube having at least five cold electrodes in conjunction with circuit arrangements for controlling the regeneration effects of the system.

A further feature relates to the organization, arrangement and relative connection of elements which go to make up an efficient and sensitive wave repeating system employing gas or vapor filled repeater devices.

Other features and advantages not specifically enumerated will be apparent after a consideration of the following detail descriptions and the appended claims.

Referring to the drawings,

Fig. 1 represents one typical form of wave repeater embodying features of the invention;

Figs. 2 to 6 show respectively modifications of the repeater of Fig. 1.

Referring more particularly to Fig. 1, the numeral 1 indicates a device of the type disclosed in application Serial No. 552,186 and comprises a bulb or envelope containing a filling of a gas, vapor or other ionizable medium. Suitably mounted within the bulb are a series of electrodes comprising a cold cathode 2, a foraminous 40 cathode 3, a control electrode 4, an auxiliary electrode 5 and an anode 6. As described in said application, the electrodes 2 and 3 are adapted to have a potential impressed thereacross sufficient to ionize the medium therebetween, and a 45 relatively high potential is impressed upon the anode 6 to accelerate the electrons from this ionized space towards and through the control electrode 4, and the auxiliary electrode 5 to the space between this auxiliary electrode 5 and the anode 6. For this purpose there is indicated 50 schematically in the drawings a suitable source of steady potential having a positive terminal 7 and a negative terminal 8. Preferably the source of potential connected to the terminals 7 and 8 is 55 above the ionizing potential of the gas or vapor

within the device 1. For example a potential of the order of 200 to 300 volts may be impressed upon the anode 6.

As indicated in Fig. 1, the positive terminal of the source of steady potential is connected through the output coupling coil 9 to the anode 6. When the device 1 is to be used as a repeater of high frequency waves the coil 9 may be shunted by a tuning condenser 10, it being understood however that the combination 9—10 is 10 representative of any one of a number of known ways of providing a tuned output circuit.

The cathode 2 is connected through a current generating resistance 11 to the negative terminal 8. For the purpose of biasing the auxiliary electrode 5 with respect to the cathode 2 the said electrode is connected by means of conductor 12 through a choke coil 13 and a bias resistance 14 to the said cathode 2. Similarly, in order to bias the auxiliary electrode 5 with respect to the cathode 3, the said electrode 5 is connected by conductor 15 through the variable resistor 16, thence to the input coil 17 to the cathode 3.

Preferably the resistor 16 is provided with a bypass condenser 18 and the coil 17 is shunted by a tuning condenser 19, it being understood that the combination 17—19 is merely symbolic of one of a number of tunable input circuits. One terminal of this tuned input circuit is connected by conductor 20 directly to the control grid 4, 30 while the other terminal is connected by conductor 21 to the cathode 3. For the purpose of providing the proper potential across the electrodes 2 and 3 the positive terminal 7 of the source of supply is connected through a voltage dividing resistance 22 to the cathode 3, and if desired this resistance may be variable in order to adjust the potential of the electrode 3 with respect to the electrode 2. When the device of Fig. 1 is to be used as a high frequency repeater it is not necessary to separately bias the control electrode 4 with respect to the cathode 3.

As indicated in the drawings the waves to be repeated are picked up by a suitable wave intercepting device such as an antenna 23 which is connected through a coupling coil 24 to ground. The coils 24 and 17 may constitute respectively the primary and secondary of any known type of high frequency coupling transformer. As indicated schematically in the drawings the resistor 16 is connected to the coil 17 by means of an adjustable tap 26 so as to vary the reaction of the output circuit on the input circuit. The output coil 9 is coupled by means of the coupling transformer, or other suitable coupling device 26, 55

to a succeeding stage or stages (not shown). Preferably, although not necessarily the cathode 3 is connected through a condenser 27 to the positive terminal 7. It has been found that 5 by connecting the auxiliary electrode 5 to the input circuit through the variable resistor 16 and the condenser 18 the amount of regeneration in a system may be easily controlled, whereas in 10 said prior application Serial No. 552,186 the auxiliary electrode 5 was connected directly to the cathode 3 which tended to limit the regeneration in the system.

The manner of operation of the system of 15 Fig. 1 will be apparent from the above description. Suffice it to say that because of the conductive filling in the tubes 1, the currents in the output circuit tend to flow through the input circuit. By means of the variable tap 25 the 20 ratio of feed back between the output and input circuits may be controlled at the same time that the desirable characteristics of a tube such as disclosed in application Serial No. 552,186 are attained.

It will be understood that the repeater of Fig. 25 1 may be used for audio amplification as well as for detection merely by providing the proper bias between the control electrode 4 and the cathode 3.

Referring to Fig. 2 there is shown a modification 30 of the system of Fig. 1, like parts in these two figures being designated by the same numerals. The repeater of Fig. 2 differs from that of Fig. 1 in certain respects, namely the auxiliary electrode 5 is coupled to the input coil 7 inductively by means of a separate winding 28. Fig. 2 also shows the cathode 3 connected through the resistor-condenser combination 29-30 and the coil 17. Instead of connecting the positive 35 terminal 7 through condenser 27 to the cathode, as in Fig. 1, Fig. 2 shows this positive terminal connected through condenser 27 directly to the control electrode 4. The functioning of the system of Fig. 2 is substantially similar to that of Fig. 1, the extent of regeneration of the system 40 being controlled by the inductive relation between the coils 28 and 17. It will also be noted that in the device of Fig. 2 the cathode 3 is not connected conductively to the negative terminal 8, but that the current return for the cathode 3 45 to the negative terminal 8 is effected through the conductive medium between the electrodes 2 and 3.

Fig. 3 shows a system substantially the same 50 as that of Fig. 1 with the additional provision of a biasing arrangement comprising a potentiometer 31 and a battery 32 for statically biasing the control electrode 4 with respect to the cathode 3. In other respects the system of Fig. 3 55 functions the same as that of Fig. 1.

Referring to Fig. 4 there is shown a modification 60 of the system of Fig. 1, wherein the auxiliary electrode 5 instead of being connected through the variable resistor 16 to an intermediate point on the coupling coil 17, is connected to the cathode 3. In other respects the device of Fig. 4 65 operates substantially the same as that of Fig. 1. It is to be noted however that in the system of Fig. 4 the extent of regeneration is very small be-

cause of the fact that the grid 5 is connected to the cathode 3. However, the small extent of regeneration that may be present can be readily controlled by the variable resistor 16.

Fig. 5 shows a system similar to that of Fig. 2 5 with the exception that the auxiliary electrode 5 is connected directly to the cathode 2 through a resistance 33.

Fig. 6 is a combination of the system of Figs. 1, 2 and 5. In this embodiment the regeneration is 10 controlled by the coupling 28 and the variable resistance 16, as well as by the variable tap 25 to the input coil 17. The static bias of the control electrode 5 with respect to the cathode 2 is provided by the resistance 33 in series with a suitable choke coil 34. The return for the output currents is provided from the point 25 to the positive terminal 7 through the resistance 29 and condenser 30 as described in connection with Fig. 2. It is believed that further description of 20 the operation of Fig. 6 is not necessary at this point.

What is claimed is:

1. In combination a wave repeater device having a filling of an ionizable medium, a cathode, a control grid and an auxiliary grid, a signal input circuit for said device, a signal output circuit for said device, and variable impedance means between said auxiliary grid and said input circuit for controlling the extent of regeneration of the waves repeated through said device. 25

2. In combination a wave repeater device having a filling of an ionizable medium, a cold cathode, a cathode, a control electrode, an auxiliary electrode and an anode within said device, an input circuit connected across said control electrode and said cathode, a connection from said auxiliary electrode to a point intermediate the terminals of said input circuit for controlling regeneration in the repeated waves. 35

3. A combination according to claim 2 in which the said connection includes a variable resistor.

4. In combination a wave repeating device having a filling of an ionizable medium, a cold cathode and four other electrodes within said device, said other electrodes including a cathode, a control electrode, an auxiliary electrode and an anode, means for statically biasing said auxiliary electrode with respect to said cathode, and means connecting said auxiliary electrode to said cathode to provide regeneration in the repeated waves. 45

5. In combination a wave repeating device having a filling of an ionizable medium, at least five cold electrodes within said device, said electrodes including a cold cathode, a control electrode, an auxiliary electrode and an anode, a source of ionizing potential connected across said cathode and anode, a signal input coil connected to said control grid, a connection from said control grid to the positive terminal of said source, and means connecting said control electrode and said auxiliary electrode for inductively supplying to said input coil energy derived 55 from the repeated signals. 60

PHILIP M. HAFFCKE.
